UNITED STATES PATENT OFFICE.

VALDEMAR POULSEN, OF FREDERIKSBERG, NEAR COPENHAGEN, DENMARK.

APPARATUS FOR UTILIZATION OF SIGNAL-CURRENTS FOR TELEGRAPHIC, RADIO-TELEGRAPHIC, OR OTHER PURPOSES.

1,198,270.

Specification of Letters Patent. Patented Sept. 12, 1916.

Application filed March 5, 1915. Serial No. 12,236.

To all whom it may concern:

Be it known that I, VALDEMAR POULSEN, a subject of the King of Denmark, residing at Frederiksberg, near Copenhagen, Denmark, have invented a new and useful Improvement in Apparatus for Utilization of Signal-Currents for Telegraphic, Radio-telegraphic, or other Purposes; and I do hereby declare the following to be a full, 10 clear, and exact description of the same.

The invention relates to an apparatus for utilization of signal currents for telegraphic, radiotelegraphic or other purposes, which can work at a very high speed under 15 the influence of even but very weak currents.

The apparatus consists of a jet of some liquid which must have at least some conductivity for electricity and may consist 20 of a strong or weak electrolyte or preferably of mercury or a liquid metal-alloy, which in some place, where it is still coherent and not dissolved into separate drops, is in contact with a substance which in connection 25 with the said liquid-jet forms a system consisting of an electrolyte and an electrode, through which system the signal currents are led by means of another electrode. Various modifications of such an apparatus are 30 diagrammatically shown in the drawing, where—

Figure 1 shows such an apparatus, in which the direction of a mercury-jet is altered by the alteration of the surface tension produced by the electrocapillary or 35 electrolytic effect, and Fig. 2 another modification in which the electrolytic effect causes an alteration of the length of the coherent part of a mercury-jet.

40 *a* designates a tube of glass or iron in which is found mercury *b*, which is under a suitable pressure and which produces a jet *c* of a diameter which is generally only a fractional part of a millimeter. The still 45 coherent part of the jet touches a piece of glass *d* which is partly encompassed by a body *e* of porous nature (carbon, bone or the like) which in some suitable manner is kept moistened with some electrolyte, for instance a solution of caustic potash. Around body *e* preferably consisting of bone is wound a platinum wire *f* serving for admission of current and at same time acting as the one electrode the mercury jet forming 50 55 the other. In case no potential difference

due to the signal currents is found between the mercury and the wire *f*, it is presumed that the mercury jet assumes the position shown in dotted lines. As soon as an alteration in the potential difference between the 60 wire *f* and the mercury arises owing to the signal currents, the consequence will be that the shape of the coherent part of the mercury jet is altered so that the jet is bent aside, for instance to the position shown in 65 full lines. The mercury drops will here impinge upon a light angle lever *g* which is pivoted at *h* and is actuated by a spring *k*. The angle lever is by means of a link *g* directly mechanically connected with the 70 siphon pen *m* and one arm of the lever plays between stops *n*, as shown. The glass piece *d* can be adjusted in relation to the jet *c*, and the jet can hereby be bent to one side or the other without the sensitivity thereby 75 undergoing any essential alteration. The intensity of the currents required for giving such a jet the necessary alteration of direction is extremely small. Of course the amount of energy in the jet can be utilized 80 for signaling in other manners than that shown by way of example. The jet may for instance be caused to close and interrupt contacts. The lever *g* and one of the stops *n* can thus be used as contact making parts. 85

As to the modifications shown in Fig. 2, the structure illustrated is founded on the phenomenon that the length of the coherent part of a mercury jet varies in accordance with the signal currents when these latter are conducted so as to pass through the mercury jet and also through a ring shaped moistened piece of bone, terracotta or the like material when such piece is in a certain proximity to the jet. The structure embodying this application of the principle of the invention includes a tube *a* containing a collection of mercury *b*. Around the constricted lower end of the tube is arranged a ring shaped moistened piece *o* of bone or the like. Of course, even with the piece absent the mercury jet, descending vertically through the opening in the lower end of the tube, breaks up into separate drops at a point some distance below the opening. This point where the cohesion of the jet ceases, depends, as is well known, upon the surface tension of the jet as compared with the molecular cohesion characteristic of the material of which the jet is composed, that is, the element mercury, 110

and also upon the velocity of the jet. The signal circuit here includes the wire *g*, the collection of mercury *b*, the piece *o*, and the wire *r*. The local circuit includes the collection of mercury *b*, the contact *p*, and the wire which joins the collection of mercury and the contact, this circuit being closed when the coherent part of the jet is intersected by the contact *p*. This contact is 10 fixed and is preferably given such a delicate adjustment that when the coherent part of the jet is at the maximum, the contact just touches the lower end of the coherent part of the jet. As explained, each signal current 15 in the signal circuit causes the coherent part of the jet to vary its length. Thus, during the passage of signal currents through the signal circuit, the jet and the contact *p* will alternately open and close the local circuit 20 in which the latter is interposed. The local circuit has a battery *B* therein, and when such circuit is closed current from the battery will flow through a relay *R* also in the local circuit. At each surge of current 25 through the relay, the latter may operate in any one of various ways to make or cause the making of a suitable record, as, for instance, by means of an auxiliary circuit, un-illustrated, but adapted to be opened or 30 closed by an operation of the relay and in turn actuating a suitable recording means.

While in the shown modifications the mercury mass proper is used for admission of the signal currents as direct positive or negative electrode, the mercury jet may also form an intermediate electrode, so that the mercury jet will be differently acted upon on two opposite sides.

The apparatus can work with direct current as well as with alternating current, and under certain circumstances it may be answering the purpose to superpose a constant or alternating potential difference over the electrodes.

Having now described my said invention and in what manner the same is to be performed what I claim and desire to secure by Letters Patent in U. S. A. is:

1. In apparatus for receiving electric signals, a jet of electrically conductive liquid, electrolytic means responsive to the signals and effective upon reception thereof to alter the jet of liquid, and receiving means responsive to the alteration of the jet to render the signals apparent.

2. In apparatus for receiving electric signals, a jet of electrically conductive liquid, electrolytic means responsive to the signals and effective upon reception thereof to deflect the jet of liquid, and receiving means responsive to the deflection of the jet to render the signals apparent.

3. In apparatus for receiving electric signals, a jet of electrically conductive liquid, electrolytic means responsive to the signals and effective upon reception thereof to deflect the jet of liquid, and receiving means in the path of the deflected jet for rendering the signals apparent.

4. In apparatus for utilizing electric signals, the combination of a jet of liquid, and means for imparting to the said liquid varying electric potentials which vary in accordance with the signal currents to cause the jet to alter its shape.

5. In apparatus for utilizing electric signal currents, the combination of a jet of liquid, means for imparting to the said liquid varying electric potentials which vary in accordance with the signal currents to cause the jet to alter its shape, and recording means operated by such alteration of the jet.

6. An apparatus for utilizing electric signal currents including a liquid jet and a physically immovable electrically functioning means for subjecting the jet to the influence of signal currents to cause the jet to alter its shape.

7. An apparatus for utilizing electric signal currents including a circuit through which these currents pass, a jet of liquid, a device always interposed in the circuit and fixedly arranged in proximity to the jet and acting to change the electric potentials of the jet as the signal currents vary.

8. An apparatus for utilizing electric signal currents including a jet of liquid, electrical means responsive to the signal currents for subjecting the jet to the influence of the signal currents to change the shape of the jet while causing the jet alternately to enter into and out of contact with said means.

In testimony whereof I affixed my signature in presence of two witnesses.

VALDEMAR POULSEN.
